UNITED STATES PATENT OFFICE.

ROBERT A. LEAM, OF YELLOW SPRINGS, OHIO.

WOOD PRESERVATIVE.

1,404,128.

Specification of Letters Patent. Patented Jan. 17, 1922.

No Drawing.

Application filed March 28, 1921. Serial No. 456,162.

To all whom it may concern:

Be it known that I, ROBERT A. LEAM, a citizen of the United States, residing at Yellow Springs, in the county of Greene and 5 State of Ohio, have invented certain new and useful Improvements in Wood Preservatives; and I do hereby declare the following to be a full, clear, and exact description of the invention, such as will enable others 10 skilled in the art to which it appertains to make and use the same.

The present invention relates to a wood preserving composition which is adapted to be applied to the surface thereof by means 15 of a brush or other article adapted to spread a liquid coating upon a surface.

The composition is applicable to posts, piles, railway ties and other timber and resists the action of moisture and the elements.

20 In preparing the composition, the ingredients herein specified are compounded in about the proportions stated, i. e.,

Boiled linseed oil	4½ gals.
Pulverized charcoal	2 lbs.
Turpentine	1 pt.

These ingredients are mixed and should

make about five gallons of the mixture which is then ready for use. The wood to be preserved is coated with the composition, the same being applied to the surface thereof by means of a brush, mop or other article capable of spreading the composition. It has been discovered that wood coated with the composition herein specified will resist the 30 action of moisture and the elements and will last an indefinite time and will not decay when buried or planted. Wooden posts, piles, railway ties and timber generally, when coated with the composition herein 35 specified, are rendered practically indestructible and are not susceptible to the action which ordinarily causes decay and rot.

What is claimed is:

A wood preserving composition embodying boiled linseed oil, four and one-half gallons, pulverized charcoal, two pounds, and turpentine, one pint.

In testimony whereof I affix my signature in presence of two witnesses.

ROBERT A. LEAM.

Witnesses:

C. S. SHELDON,
CHAS. H. ELLIS.
